UNITED STATES PATENT OFFICE.

WILLIAM A. MCCOY, OF BEMAN, KANSAS.

DEVICE FOR ADJUSTABLY ATTACHING WEED-CUTTERS TO CULTIVATOR-STANDARDS.

SPECIFICATION forming part of Letters Patent No. 531,054, dated December 18, 1894.

Application filed March 8, 1894. Serial No. 502,250. (No model.)

To all whom it may concern:

Be it known that I, WILLIAM A. MCCOY, a citizen of the United States, residing at Beman, in the county of Morris and State of Kansas, have invented certain new and useful Improvements in Connectors Between Weed-Cutter Shanks and Cultivator-Standards; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention relates to certain improvements upon the means, shown by me in my United States Patent No. 503,932, for connecting the shank of a weed cutter with a cultivator standard.

The special object of my invention is to make a connector which can be readily applied to cultivators with iron or wooden beams; also to allow a curved movement to the diamond point of the weed cutter so that it may be set at any desired slant to suit the varying crooks or bends in the standards of different cultivators.

Figure 1 of the drawings is a perspective view of my connector, showing its application. Fig. 2 is a view of the connector all in vertical section except the standard which is in perspective; Fig. 3, a detail view of the casting which comes between the shank-casting and the cultivator standard; Fig. 4, a detail view of the casting which goes behind the cultivator standard and Fig. 5 a cross section on line $\alpha\alpha$ of Fig. 2.

In the drawings, A represents the casting on which the weed cutter is bolted through the hole a and opening a' . Between the concaved point a^2 and the heel or flange a^3 is a

concaved body a^4 in which rest the washer b and nut b' on the threaded end of a screw-bolt B. The shank of this bolt passes through a hole a^5 in the middle of the casting A and a slot c^5 in the longitudinal middle of the casting C while its head rests in a groove c^3 that surrounds the slot on the side next to the standard D which I prefer to be round.

The casting C has a cavity c^4 in which the body a^4 of casting A is firmly retained by the bolt and nut with washer b . On the opposite side to the concavity c^4 are formed two end-grips $c^2 c^3$ of V-shape and serrated on the opposite inner edges, and two side-pockets $c' c'$ with slots c , in the upper side. E E are two bolts whose heads are placed in these pockets while the shanks pass through the slots c and also through the slots $f f$ of the back casting F.

By this construction, the diamond point may be adjusted to any desired slant, the cutter may be thrown forward far enough to allow the use of a flat wrench on top, and any width of standard may be fitted with the connector.

Having thus described all that is necessary to a full understanding of my invention, what I claim as new is—

The casting A having holes a a' , concave point a^2 , heel or flange a^3 , concave body a^4 and hole a^5 ; the screwbolt B with washer b and nut b' ; the casting C having the slots c c^5 , groove c^3 , concavity c^4 and grips $c^2 c^3$; the bolts E E and casting F with the slots $f f$, all combined and arranged as shown, for the purpose set forth.

In testimony whereof I affix my signature in presence of two witnesses.

WILLIAM A. MCCOY.
